UNITED STATES PATENT OFFICE.

WILLIAM DWIGHT ELWELL, OF MARYSVILLE, KANSAS.

CUFF-HOLDER.

SPECIFICATION forming part of Letters Patent No. 436,222, dated September 9, 1890.

Application filed June 27, 1889. Renewed August 7, 1890. Serial No. 361,354. (No model.)

To all whom it may concern:

Be it known that I, WILLIAM DWIGHT ELWELL, a citizen of the United States, residing at Marysville, in the county of Marshall and State of Kansas, have invented certain new and useful Improvements in Cuff-Holders, of which the following is a specification, reference being had therein to the accompanying drawings, in which—

10 Figure 1 is a perspective view of a cuff having attached to it one of my improved holders; Fig. 2, a bottom view of one of the holders; Fig. 3, a similar view of a slight modification of the device; Fig. 4, a perspective view 15 of one of the spring holding-arms.

The object of the invention is to provide an extremely simple and inexpensive device for adjustably attaching a cuff to a shirt-sleeve, as will be fully hereinafter specified.

20 In the drawings, *a* designates a bar of suitable length provided with a sliding clasp or clip *b*. Attached to the under side of this bar, near its forward end, are two spring-arms *c c*, provided with hooks at their rear ends.

25 The tendency of these arms is to press outwardly. The arms may be formed integral with each other and connected by a small coil located and secured to the lower side of the bar, as shown in Fig. 2.

30 The device is applied as shown in Fig. 1—that is to say, the spring-arms are pressed to-

gether, as shown in Fig. 2, and the hooks inserted in the rear button-hole of the cuff, the outward tendency of the arms and the hooks serving to securely attach the device to the 35 cuff. The wristband of the shirt-sleeve is then inserted in the clasp and the cuff is attached. By reason of the adjustability of the clasp, the cuff may be readily adjusted with respect to the end of the coat-sleeve.

40

As shown in Fig. 3, the bar *a* may be formed of two wires, and these wires may be continuations of the spring-arms.

Having thus fully described my invention, what I claim, and desire to secure by Letters 45 Patent, is—

As an improved article of manufacture, a cuff-holder consisting of the bar *a*, provided with an adjustable clasp to clamp the shirt-sleeve, and a pair of spring-arms *c*, secured to 50 the forward end of the said bar *a* and extending rearwardly therefrom, these arms being provided with hooks to engage the button-hole of the cuff, the tendency of these arms being to spread, as and for the purposes set 55 forth.

In testimony whereof I affix my signature in presence of two witnesses.

W. DWIGHT ELWELL.
